UNITED STATES PATENT OFFICE.

GEORGE C. THOMAS, OF WATERBURY, CONNECTICUT.

DESIGN FOR A LAMP-BODY.

SPECIFICATION forming part of Design No. 16,078, dated May 5, 1885.

Application filed March 9, 1885. Term of patent 7 years.

To all whom it may concern:

Be it known that I, GEORGE C. THOMAS, of Waterbury, in the county of New Haven and State of Connecticut, have invented and produced a new and original Design for a Lamp-Body, of which the following is a specification.

This design relates to stand-lamps.

The accompanying drawing illustrates a lamp-body embodying my design.

10 A designates the lamp-reservoir. It has a convexed top, a , provided with one or more moldings. Below the top is a cylindric portion, a' . Below the cylindric portion a' the reservoir tapers as it extends downwardly, 15 and has a convexed portion, a'' , a molding, a''' , and a curved portion, a'''' .

Below the curved portion a'''' is a circular projection, B. The projection B has a convexed upper portion, b , a convexed lower portion, b' , and an intermediate bead.

Below the projection B is a molding, b'' . Below the molding b'' is a standard, C. Said standard C below the molding b'' has a general upward taper, and is ornamented at the base with moldings. 25

Above the reservoir A is a burner, E.

What I claim as my invention, and desire to secure by Letters Patent, is.—

The design for a lamp-body, consisting of the reservoir tapering as it extends downwardly, 30 the standard tapering as it extends upwardly, and the circular projection B between them, substantially as shown and described.

GEO. C. THOMAS.
